GAME SCORING CARD

Rebecca Y. Card, 2923 Fairfax St., and David C. Card,
Jr., 4137 Irving St., both of Denver, Colo.

Filed Oct. 10, 1960, Ser. No. 62,430

Term of patent 7 years

(Cl. D34—15)

Fig. -3

Fig. -2

Fig. -1

bridge score

table couple

Fig. 1 is a front elevational view of a game scoring card according to our ornamental design;

Fig. 2 is a side elevational view of the card of Fig. 1; and

Fig. 3 is a rear elevational view of the card of Fig. 1.

The dominant feature of our design resides in the portions shown in full lines.

We claim:

The ornamental design for a game scoring card, as shown and described.
